ABSTRACT

A pad, capable of formation into a roller, contains a heat generating formulation, the temperature of which can be controlled. Upon addition of water, the heat is generated at the predetermined rate for a period of time sufficient to provide a temporary setting of hair.

CONTROLLED HEAT RELEASE PAD
CROSS-REFERENCES TO RELATED
APPLICATION

This application is related to my co-pending application, Ser. No. 79,447, filed Oct. 9, 1970.

BACKGROUND OF THE INVENTION

The setting of human hair, a proteinaceous material, either by waving or curling, is a subject which has received considerable attention. A variety of electrical devices and materials are presently marketed to accomplish hair setting in a variety of manners. Some of the devices presently marketed for this purpose are heated so as to more easily accomplish the setting of the hair which, because of its proteinaceous nature, will set when wrapped about a heated roller. In particular, various electrically heated rollers have been manufactured but these provide obvious drawbacks because of the necessity for electrical current.

Other devices have been provided which utilize machineless or cold-waving methods for permanent waving of the hair, and these also have drawbacks because of the general requirement that chemical compounds, particularly caustic compounds, be brought into direct contact with the hair and scalp of the user.

Prior patents have described other types of pads, such as pads particularly employable for permanent waving of hair, these pads utilizing heat chemically generated within the pad. One example of such a prior patent is U.S. Pat. No. 2,239,410—Bonat. However, because the materials described in this patent do not provide for a controlled heat generation, there was often an excessive generation of heat. In those situations where the pad is employed as a roller to set the user's hair, there is the danger of injury to the hair and/or scalp of the user. In other situations, there was no assurance of the correct heat to provide proper setting of the hair, as when the hair is formed as a wig.

SUMMARY OF THE INVENTION

In my co-pending application, previously referred to, I have described a structure and formulation for a heat generating pad to be used in setting human hair. The formulation and structure provide for controlled generation of heat, for a controlled period of time, so that the hair may be set without injury to the hair and/or scalp of the user. In accordance with the present invention, I have developed a separate formulation which, through proper variation, can be employed to form a pad similar to that described in my co-pending application, where the temperature generated by the composition is such as to allow for setting of human hair without injury to the hair or scalp of the user, or to provide a pad which can be used for setting hair not attached to the user's scalp, i.e., a wig. In the latter case, because the hair is not directly attached to the user's scalp, higher temperatures may be employed. However, even in these cases, too high a temperature may result in damage to the hair or hair-like filaments which constitute the wig and, accordingly, control of the temperature generated is important. Further, as is obvious, if the temperature of the roller is not sufficiently high, or is not generated or maintained over a sufficient period of time, then inadequate setting will result.

In accordance with the present invention, the formulation is prepared in two parts. The first part, in essence, is the material which provides the heat when actuated by water. However, the second part acts as an activator for the first part. Thus, the amount of the second part employed controls the temperature generated by the pad and variation of the amount of the second part employed, with relation to the first part, acts to determine the use to which the pad can be put. I.e., smaller amounts of the second part will provide for a pad, capable of formation into a roller, which can be applied directly to human hair and to a human scalp. Increased amounts of the second part, on the other hand, provide for a pad, capable of formation into a roller, which is more suited to use in setting wigs, where a higher temperature is desirable.

In addition to the particular formulation, my invention contemplates a particular pad structure. The formulation employed according to the present invention, is in powder form. Accordingly, my invention contemplates the use of a multi-layer pad structure where at least one of the layers is corrugated so as to retain the heat generating formulation in place. Proper formation of this corrugation will also act to assure that the correct amounts of the heat generating formulation are contained within a given pad.

DESCRIPTION OF THE DRAWINGS

30 In the accompanying drawings,
 FIG. 1 is a plan view, partially broken away, of the pad of the present invention;
 FIG. 2 is a sectional view along the line 2—2 of FIG. 1;
 35 FIG. 3 is an enlarged view of a portion of FIG. 2;
 FIG. 4 is a sectional view along the line 4—4 of FIG. 1; and
 FIG. 5 is a view of the pad of FIG. 1, made into the roller, ready for application in a waving or setting operation.

DETAILED DESCRIPTION OF THE PREFERRED EMBODIMENTS

45 Referring to the drawings, the various layers of the pad of the present invention are illustrated. In particular, this pad includes a metal foil layer 1, a layer of stiffener paper 2, and a corrugated sheet 3 within which the heat generating formulation of the present invention is contained. Overlying the corrugated layer, and more particularly that side of the corrugated layer in which the heat generating formulation 4 is contained, is an absorbent layer 5. A portion of the metal foil layer, near an edge, is provided with a pressure sensitive adhesive 6 and a non-blocking paper covering 7 which prevents adherence of this pressure-sensitive layer to a further surface until the desired time. Surrounding each of the edges of the pad is a synthetic resin strip 8 which acts to hold the various layers together and also acts to prevent loss of the heat generating formulation contained within the corrugations of layer 3. In addition, strips 9 of the same synthetic resin overlie portions of the pad in order to aid in retaining the heat generating formulation in place.

60 Referring to the specific layers in more detail, the foil layer 1, preferably an aluminum foil, acts as a heat conductor so as to distribute the heat evenly over the sur-

face of the roller. Preferably the thickness of this aluminum foil layer is about 0.35 mil. Of course, there may be some variation in the thickness of the foil layer and the foil may be from about 0.1 to 1 mil, or more, in thickness.

The stiffener layer is preferably formed of a 10-point, relatively stiff paper, such as Kraft paper. This stiffener layer provides the necessary dimensional stability after the pad has been formed into a roller, and further acts to retain heat.

In many instances, it will be desirable to form the stiffener layer and the foil layer as an integral sheet prior to formation of the pad. Thus, a layer of Kraft paper may be coated with a thin film of metal, such as aluminum, by a variety of techniques known in the art, including the lamination of two layers. This combined sheet would thus form both the stiffener layer 2 and foil layer 1 of the pad of the present invention. In either event, the stiffener layer is preferably about 10 mils thick and the thickness of this layer may vary from about 5 to 25 mils.

The carrier layer 3 of the pad is the layer which holds the heat generating formulation. As previously discussed, and as indicated in the drawings, this layer is a corrugated layer. The heat generating formulation of the present invention is held within the corrugation on the side opposite the foil layer 1 and stiffener layer 2. In general, this corrugated layer 3 can be formed of any material which does not react with the heat generating compound, either before or during reaction, and which is capable of being heat bonded to the top layer of the pad, as will be later described. In general, this carrier layer can be formed of cellulosic paper having a thickness of about 5 to 10 mils, preferably about 7 to 8 mils.

The heat generating formulation of the present invention, as previously indicated, is formed in two parts. Part A comprises the following components in the amounts indicated:

Material	Amount
Potassium Permanagate	0.5-1.0 part
Powdered Iron	10-15 parts
Cupric Oxide	0.25-0.50 part
Tartaric Acid	5-8 parts

Part B of the formulation aids in activating Part A. The constituents of this component are:

Material	Amount
Silica	50-60 parts
Aluminum	9.5-12 parts
Cupric Sulfate	10.5-12 parts
Sodium Nitrate	5.5-7 parts
Sodium Chlorate	10-12 parts

In addition, Part B may contain small amounts of other materials, such as 0.1-0.5 part of ferric oxide and 3-6 parts sodium chloride.

For use in forming the controlled heat roller which is applied directly to human hair, approximately 21 parts of Part A should be mixed with from 0.75 to 1 part of Part B. A total of from about 15 to 20 grams of the mixture is applied for each 2 1/4 inch by 2 1/4 inch pad.

When the heat generating pad of this invention is not to be applied directly to the human scalp, i.e., when the pad is to be employed in setting or curling a wig, for example, then the amount of activator, Part B, may be increased. In that situation, there is an approximate 1 to 1 ratio of Part A and Part B. Variations in this ratio are permitted and the ratio may vary from 1:0.1 to 1:1.1 of Part A to Part B. From about 12 to 17.5 grams of the mixture is then employed for each 2 1/4 inch by 2 1/4 inch pad.

The controlled heat pad, for application directly to human hair, will begin to generate vapor, after application of water to absorbent layer 5, in about one-half minute. The maximum temperature of 135°-150° F. is quickly attained and this temperature is maintained for a period of about 15 to 25 minutes. With the pad for application to wigs, a temperature of 160°-180° F. is attained in about 1 1/2 minutes. This temperature is maintained for from about 30 to 40 minutes. The temperatures and times set forth above have been found to be the ideal for setting, respectively, human hair and wig hair or filaments.

In Part A above, the potassium permanagate is employed in the form of a finely comminuted powder. This acts as an oxidizer for the iron powder which is also a heat conductor and distributor. The iron powder, preferably, is of a size which will pass a U.S. No. 50 sieve. The cupric oxide is a catalyst for the reaction of the potassium permanagate and iron powder, and is, itself, employed in powder form. The tartaric acid is important in modulating the heat generation of the formulation and is also employed in the form of a powder.

With regard to Part B, the silica acts as an inert material for distributing and dispersing the remainder of the formulation. The aluminum powder, as the iron powder of component A, acts as a heat conductor and also aids in generation of heat, as does the cupric sulfate which is employed in its anhydrous form. The sodium nitrate acts as a catalyst and the sodium chloride, employed in a finely comminuted form, acts as an oxidizer in the same manner as the potassium permanagate of Part A. The ferric oxide and sodium chloride are additional stabilizing agents.

Part A and Part B are mixed in the desired proportion, as indicated above, and are then fed in a dry state to the corrugated layer 3. They may be applied in any manner so as to obtain a uniform distribution of the powder within the corrugations in the amounts indicated. For example, a doctor blade may be employed, or any other manner of placing the powder within the corrugations as is known in the art.

The final layer of the pad, absorbent layer 5, is a heat sealable paper material which has a wicking action. The heat sealability is required in order to bond the absorbent layer to the apexes of the corrugated layer 3. Bonding of the absorbent layer 5 to the corrugated layer 3 aids in retaining the dry, heat generating mixture in a properly distributed manner. Examples of papers which can be employed are those manufactured by C. H. Dexter Company under Numbers 24 and 313. They are 14 No. papers generally having a thickness of from about 6 to 15 mils and a water absorption capacity exceeding 0.2 gram per square inch. A test for the paper involves a modification of ASTM Standard D 726-43T. In this modified test, porosity is defined as the average number of seconds for displacement of 400

milliliters of air through a 1 square inch area having four thicknesses of the material. Employing this test, the porosity of the absorbent layer 5 employed should be from about 0.5 to 10 seconds, preferably about 5 seconds on a Gurley densometer.

Following formation of the pad with the layers described, the edges of the pad, and some portions in the center of the pad, are crimped as indicated in the areas 8 and 9. This crimping is to provide for easier application of a bonding resin which, after application, aids in retaining the dimensional stability of the pad. The resin employed is generally a thermoplastic resin adhesive which is placed on the pad in the desired form and the entire pad is then heated to soften the resin, following which the pad is pressed to bond the resin. Upon cooling, a seal is effected. The resin should be one which will maintain the seal at temperatures above 200°-220° F. so that the seal is not broken upon generation of heat. Included among resins which can be employed for this use are polyvinyl resins, particularly a vinyl chloride-vinyl acetate copolymer. Additionally, a properly plasticized cellulose derivative can be used.

To employ the pad described in accordance with the foregoing disclosure, it is formed into a roller in the manner illustrated in FIG. 5. Specifically, the pad is bent into a roll form. As an added convenience, a cylindrical form (not illustrated) may be employed. The blocking paper layer 7 is removed and portion 9 of the pad surface is applied over the pressure sensitive adhesive 6 and firmly pressed so as to bond this edge to the pressure sensitive layer and thus complete formation of the roller. In place of the pressure sensitive adhesive, other means of joining one end of the pad to the other for formation of the roller can be used. Such means include the formation of a slot through the entire pad with a tab formed on stiffening layer 6 which is inserted within the slot. Other methods of holding the roller form will be apparent to those skilled in the art.

After formation of the roller, water is applied to the inner, absorbent surface layer 5. This water reacts with the heat generating formulation 4 carried within corrugations of sheet 3. Within $\frac{1}{2}$ to 1 $\frac{1}{2}$ minutes, depending upon the type of pad employed according to this invention, heat generation begins. This allows sufficient time for properly winding the user's hair or the fibers of a wig about the formed roller. Heat generation continues for a period of time, as previously disclosed. This heat is sufficient to create a temporary set in the hair, but the temperature is not sufficiently high to injure the hair or scalp of the user, when using the controlled heat roller of the first embodiment, nor to damage the fibers of a wig, when using the pad according to the second embodiment.

In addition to the specific materials employed in the heat generating formulation, as previously disclosed, other materials may be placed within the pad, either as a part of this formulation, or more preferably in absorbent layer 5. Such materials may include various heat activated conditioners which are inert when the pad is stored, but which become activated when the temperature of the pad rises above 135° F. Such materials may include proteins to enhance the quality and appearance of the hair.

In addition to the controlled heat provided by the specific construction and formulation of the present

pad, a certain amount of heat control is also obtained through the inherent structure of the roller which allows heat to be dissipated into the surrounding air through the openings in the ends of the roller. If it is desired that this heat be retained for an additional period, a cap can be used. In that situation, the rollers are formed as indicated and the hair wound about them. The absorbent layer of the pad is wetted, employing an aerosol type spray for wetting, and the cap is then placed over the head for the desired period of time. Since, inherently, the formulation described will generate a temperature only within the desired range, the temperature within the cap or bonnet will not rise above this level, but the heat may be sustained for a longer period of time.

The invention has been described in detail, with particular reference made to preferred embodiments thereof, but it will be understood that variations and modifications can be effected within the spirit and scope of the invention as described hereinabove and as defined in the appended claims.

I claim:

1. A pad for use in hair setting and adapted to generate controlled amounts of heat upon the application of water comprising:

a. a first layer adapted to distribute the heat and maintain the dimensional stability of the pad;

b. a second layer, adjacent said first layer, but separated from said heat distributing area, including a heat generating formulation capable of generating heat, following the application of water, at a controlled rate for a period of time sufficient to temporarily set the hair, said formulation being formed in two parts, said first part consisting essentially of potassium permanganate, iron powder, cupric oxide and tartaric acid; and said second part comprising silica, aluminum, cupric sulfate, sodium nitrate, and sodium chlorate; and

c. an absorbent layer adjacent the side of said second layer carrying said heat generating formulation, and adapted to receive water for contact with said heat generating formulation.

2. The pad of claim 1 wherein said first layer is formed of two distinct materials, the first a heat distributing foil and the second a Kraft paper.

3. The pad of claim 1 wherein said second part also contains ferric oxide and sodium chloride.

4. The pad of claim 1 wherein the ratio of the first part of said heat generating composition to the second part of said heat generating composition is approximately 20:1.

5. The pad of claim 1 wherein the ratio of the first part of said heat generating composition to the second part of said heat generating composition to the second part of said heat generating composition is from 1:0.1 to 1:1.1.

6. The pad of claim 5 wherein said ratio is 1:1.

7. The pad of claim 1 having, in addition, a protein material, inert at room temperature but generated at a temperature of at least 135° F.

8. A pad capable of generating heat at a controlled rate for a sustained period of time upon the application of water comprising:

a. a first layer adapted to distribute the heat and maintain the dimensional stability of the pad; aluminum, sodium nitrate

b. a corrugated layer, adjacent said first layer, but separated from said heat distributing area, having contained within the corrugations furthest from said first layer a heat generating formulation formed in two parts, said first part consisting essentially of potassium permanagate, iron powder, cupric oxide and tartaric acid; and said second

5 part comprising silica, aluminum, cupric sulfate, sodium nitrate and sodium chloride; and c. an absorbent layer adjacent the side of said corrugated layer carrying said heat generating formulation, and adapted to receive water for contact with said heat generating formulation.
